UNITED STATES PATENT OFFICE.

BENEDICT H. BENDER, OF MILWAUKEE, WISCONSIN, ASSIGNOR TO BENDER-ZIMMER COMPANY, OF MILWAUKEE, WISCONSIN, A CORPORATION OF WISCONSIN.

CAP.

Application filed May 5, 1921. Serial No. 467,148.

To all whom it may concern:

Be it known that I, BENEDICT H. BENDER, a citizen of the United States of America, residing at Milwaukee, in the county of Milwaukee and State of Wisconsin, have invented certain new and useful Improvements in Caps, of which the following is a specification.

This invention relates to certain new and useful improvements in caps particularly serviceable as a neat and comfortable head covering for use in the cold season.

The invention contemplates the provision of an improved cap, preferably of knitted material and so constructed as to include normally inoperative members capable of being employed in various ways for obtaining the desired warmth for the back of the neck and the ears of the wearer, which members may be readily placed in operative position as well as relatively arranged in different relations while maintaining a neat appearance.

An object of the invention is to construct a cap of a minimum number of parts of extremely simple form which may be readily assembled for producing a cap structure, and wherein the parts are knitted with the direction of the wales such as is calculated to combine great durability and elasticity.

Other objects will appear as the nature of the invention is better understood and the same consists in the novel form, combination and arrangement of parts hereinafter more fully described in connection with the accompanying drawings and in which like characters of reference indicate corresponding parts throughout the several views.

In the drawings,

Figure 1 is a front elevational view of a cap constructed in accordance with the present invention with the cuff and neck and ear flap members inoperatively disposed, the neck and ear flap being disposed inwardly of the body of the cap,

Figure 2 is a rear elevational view of the device shown in Figure 1,

Figure 3 is a view similar to Figure 1 with the neck and ear flap withdrawn from the inside of the cap body to operative position,

Figure 4 is a side elevational view of the cap shown in Figure 3,

Figure 5 is a transverse sectional view taken upon line V—V of Figure 1,

Figure 6 is a view similar to Figure 4 with the neck and ear flap inoperatively disposed against the outer surface of the cuff member,

Figure 7 is a view similar to Figure 4 with both the cuff and flap members operatively disposed in lowered position,

Figure 8 is a diagrammatic plan view of the blank from which the body of the cap is formed,

Figure 9 is a view similar to Figure 8 of the cuff blank, and

Figure 10 is a view similar to Figure 9 of the neck and ear flap blank.

Referring more in detail to the several views, the present invention embodies a cap including a body portion 5 preferably formed of knitted material and shaped to snugly fit the head of the wearer and having an external cuff 6 encircling the same adjacent its lower margin, the cuff 6 being a band of material with one longitudinal edge stitched to the lower edge of the body 5 and with the remaining portion of the cuff free for a purpose which will presently become apparent, the front of the cap being indicated by the provision of spaced buttons 7 or the like stitched to the cuff 6 as shown clearly in Figure 1 whereby the cap is given an ornamental appearance.

An arcuate combined neck and ear flap 8 has a portion of its edges also stitched to the lower edge of the body 5 and with its remaining portion free, the flap 8 being of lesser length than the cuff 6 for the purpose of providing an open face at the front of the cap for permitting clear vision when the flap is lowered or operatively disposed.

As shown in Figure 8, the body 5 is constructed of a blank of knitted fabric having a straight lower edge as at 9 and knitted in connected sections 10, adjacent ones of which have the direction of the wales substantially at right angles so that adjacent pairs of the sections 10 produce the well known "herring bone" effect, and the upper edges of which sections are formed oblique to the longitudinal edge 9 and parallel to the direction of the wales of said sections 10. The intermediate pairs of sections form inverted V-shaped projections 11 as do also the end sections 10 when they are joined by sewing along their free edges for providing the completed body portion 5.

When the blank is brought into annular formation as above described, the V-shaped projecting portions 11 are brought inwardly toward each other and their meeting oblique edges are then sewed together for forming the closed end of the body portion as clearly shown in Figure 1, the stitching being indicated at 12. The edges of the projecting portions 11 are provided with edges in the

form commonly known as selvage edges so that ravelling at this point is unlikely and so that the stitching will produce a durable construction at the closed end of the body. Also, the provision of the oblique direction of the wales not only gives an ornamental effect but insures the provision of a strain resisting blank for forming the body portion whose stretching qualities are reasonably limited.

20 The cuff 6 is formed of a rectangular blank of knitted material and of elongated form as indicated at 6' in Figure 9, the direction of the wales being longitudinal as indicated, so that the cuff will be slightly 25 more yieldable or capable of stretching than the body portion as is necessary for the required ease of lowering the cuff for covering the back of the neck and ears as shown in Figure 7, the shorter end edges of the blank 6' being joined by stitching as indicated at 12 in Figure 2.

The neck and ear flap is also formed of a knitted blank of elongated form with the direction of the wales longitudinal, the blank being denoted at 8' in Figure 10, and the end edges of the blank being rounded off as at 13 so as to provide longitudinal edges of the blank of differing lengths with the shorter edge and rounded off end edges 40 stitched to the lower edge of the body 5, the blank 8' being of lesser length than the cuff blank 6' so that when said blank 8' is stitched to the body 5, the portions of the longer longitudinal edge which then form 45 the end edges of the latter blank are in sufficient spaced relation to permit clear vision when the flap is in lowered operative position as shown in Figure 3.

The combination of the cuff 6 and flap 8 on the body 5 has several advantages as clearly illustrated in Figures 1 to 7 inclusive. If a desired effect embodying plainness is wanted and if the weather is sufficiently warm to render unnecessary covering 55 of the back of the neck and the ears, the flap 8 is folded into the body 5 and the cuff 6 is left encircling the lower margin of the body as illustrated in Figures 1, 2 and 5. If a more fancy appearance is required, the flap 60 8 may be folded outwardly upon the cuff 6 so as to partially cover the rear and side

portions of the latter as shown in Figure 6, this arrangement of the cuff and flap also being desirable in case the covering of the back of the neck and the ears is not desired. 65

When the weather is only cool, it may be desired to provide only a single covering for the back of the neck and ears, in which case the cuff will be left in its normal position and the flap 8 lowered as shown in Figures 3 and 4. However, should very cold weather be experienced, additional warmth for the back of the neck and ears may be had by leaving the flap 8 lowered and then folding the sides and rear portions of the 75 cuff 6 down onto the flap 8 as shown in Figure 7, the front portion of the cuff being left raised for permitting clear vision and presenting a pleasing appearance.

In view of the foregoing, it is believed 80 that the construction and manner of use as well as the advantages of the present invention will be readily understood and appreciated by those skilled in the art.

Minor changes may be made without departing from the spirit and scope of the invention as claimed. 85

What is claimed as new is:

The method of manufacturing a cap from a series of blanks constituting a body portion; a cuff; and an ear and neck flap where- 90 in an elongated knitted blank is employed as the body portion and comprises connected sections with the direction of the wales oblique to the longitudinal axis of the blank 95 and with the direction of the wales substantially at right angles with respect to the adjacent ones of said sections, the lower longitudinal edge of the blank being straight and the upper edges of the sections being parallel to the wales of the latter whereby intermediate pairs of sections are formed with inverted V-shaped projecting portions, said 100 projecting portions being brought inwardly and having their meeting edges stitched together so as to form a closed end, a second elongated knitted blank forming the cuff and having the direction of the wales longitudinally of the blank with one longitudinal edge secured to the lower edge of the first 110 blank and a third elongated knitted blank forming the ear and neck flap with the direction of the wales longitudinal of the blank, said blank having curved end edges 115 providing longitudinal edges of differing length with the shorter longitudinal edge and curved end edges secured by stitching to the lower edge of the first blank, and with the portions of the longer longitudinal edge 120 which then forms the end edges of the third blank terminating in spaced relation.

BENEDICT H. BENDER.
